APPARATUS FOR CONCENTRATING MATERIALS

Application filed October 23, 1926. Serial No. 143,614.

This invention pertains to an apparatus for concentrating materials, such as ores and the like, and involves the use of a concentrating table of improved construction.

A well known method of concentrating materials, such as ores and the like, consists in passing the material over the deck of a concentrating table. Such a table is usually given an inclination from the feed side downwardly to the discharge side and is mounted and adapted for oscillating movement endwise of the table. This movement is usually such as to tend to cause a travel of the material endwise of the table from the head end toward the tail end. In order to assist in guiding the material during such travel, the deck is equipped with ridges or riffles providing a series of grooves therebetween in which the material travels.

It is well known that in the operation of a concentrating table of this type, the material on the deck stratifies according to the specific gravity of the particles. The particles of greater specific gravity, which are usually the particles containing the valuable mineral, sink to the lower stratum, while the lighter particles constituting the gangue form the upper stratum. In concentrating an ore, the material is usually considered as divided into three strata as it moves over the deck of the table—namely, a lower stratum consisting of the free mineral and known as concentrates, an intermediate stratum consisting of mineral attached to sand and known as middlings, and an upper stratum consisting of sand or material containing minimum value and known as tailings.

In practice the riffled deck of the table has inclination toward the lower or tailings discharge side. The riffles prevent the flow of the whole mass of material on the deck from washing over the tailings discharge side and guide the particles stratified on the deck in the grooves or channels between the riffles toward the concentrate discharge end of the table. The width of the space between the riffles and the height of the riffles determine the amount of material carried forward by the grooves or channels between the riffles

toward the concentrate discharge end of the table.

An object is to provide a concentrating table having riffles so distributed as to improve the completeness of separation of the material and to increase the amount of material handled.

Another object is to provide a table with riffles so arranged as to force out the gangue from the stratified material so as to increase the rapidity of separation.

Further objects will appear from the following description taken in connection with the accompanying drawings, in which

Figure 1 is a plan view of the deck of a concentrating table embodying this invention;

Figure 2 is a partial section taken on line 2—2 of Figure 1; and

Figures 3 and 4 are similar sections taken, respectively, on lines 3—3 and 4—4 of Figure 1.

Referring now to the drawings, 1 designates the head motion end of the table and the arrow 2 represents the approximate point of connection of the driving mechanism, not shown, and the direction of differential reciprocation of the deck. Mechanism for imparting this movement to the table is well known in the art, and therefore requires no detailed description. 3 represents the feed box and water board side of the deck, the feed coming on the table at the corner 4. The end 5 is the concentrate discharge end of the deck. The middlings are discharged adjacent the corner 6, while the tailings come off along the edge 7. In practice this edge is usually somewhat lower than the side 3, so that material not caught and carried forward by the grooves or channels between the riffles will flow by gravity across the deck.

As the heavier particles of mineral seek the lower stratum soon after coming on the table, a number of straight riffles 8 are provided which run substantially parallel to each other along the feed side of the deck. Some of these riffles may run practically all the way to the concentrate discharge end 5 of the table. These riffles are straight and of uniform width, with comparatively wide

spaces or channels between them, so that these heavier particles will be carried directly and rapidly toward the concentrate discharge end. As the riffles approach the end 5, they are preferably tapered in height so as to wash out progressively more and more of the gangue in order that only the cleanest concentrates are carried forward to the extreme concentrate end of the table. The number of 10 riffles 8 may be more or less, as required by the circumstances of the particular case. This arrangement for the first few riffles on the deck effects a quick separation of the heavier particles of mineral and prevents 15 packing of the bed of material on the deck due to the presence of finely ground mineral in the feed. This keeps the material generally in a more fluid condition on the upper part of the deck and accelerates segregation 20 of the mineral content which makes it possible to improve both the grade of the concentrates and the amount recovered. By continuing forward to the extreme concentrate end of the deck a few of the upper riffles, the 25 coarse particles of clean concentrates are carried forward in a bed of fine concentrates and protected by the riffles, whereas if coarse particles of concentrates are carried forward by riffles terminating as usual along a diagonal 30 line, such as C—D, the action of the flow of the wash water across the deck against the large surfaces of these larger particles washes a considerable portion of this valuable coarse concentrate into the middlings product. 35

With the major portion of the free concentrates removed by the upper riffles on the deck, the purpose of the remaining riffles is to effect as perfect a separation as possible between the remaining concentrates, middlings 40 and tailings.

It is well known that minerals and middlings will readily stratify between straight riffles on the deck of a concentrating table when the grooves or channels between the 45 riffles are relatively wide and deep. With such wide and deep grooves, however, both the mineral and the middlings are retained in the groove, and a considerable quantity of the gangue is carried forward with the 50 material carrying values.

In order to overcome the tendency to carry forward the gangue along with the valuable mineral and yet take advantage of relatively wide, deep grooves for the stratification of 55 particles of concentrates and middlings, a special arrangement of riffles is provided in accordance with this invention.

All of the riffles on the table run in a general parallel direction. The surface of the 60 table may be considered as divided into nearly equal zones, those zones being bounded approximately by the diagonal lines E—F, A—B and C—D. In that part of the table between the lines E—F and the tailings discharge side 7, the riffles are relatively narrow

and widely spaced and the grooves between them are straight. In that part of the table between the lines E—F and A—B, the riffles increase progressively in width, so that the grooves between them are tapered, becoming 70 gradually narrower toward the tail end of the table. In that part of the table between the lines A—B and C—D, the riffles are relatively wide and the grooves between them relatively narrow. Riffles and grooves are, however, 75 straight as regards their width. The riffles are also tapered in height progressively toward the tail end of the table, growing gradually less in height as they approach that end. The main body of riffles, other than 80 the riffles 8 previously described, terminate along a diagonal line C—D, and the remaining portion of the table between this line and the concentrate discharge end 5 is without riffles. Figures 2, 3 and 4 illustrate this arrangement of riffles. These figures show the 85 relative heights and widths of the riffles on the different portions of the table indicated.

The operation of this table is as follows: As the material comes on at the feed corner 4, it begins immediately to stratify and the heavier mineral is separated out by the riffles 8 as described above. The remaining material flows downwardly across the deck and stratification takes place in the grooves between the remaining riffles. In the zone 9 between the line E—F and side 7 of the table, the mineral and the middlings stratify within the wide, deep grooves on this part of the table, while the tailings are washed over and discharged. The stratified material in the grooves is then moved lengthwise of the table by the action of its reciprocating movement. This material travels through the zone 10 between the line E—F and the line A—B. 105 As the material passes through this zone it encounters gradually narrowing grooves. As the material in each groove is arranged in a pile having a lower stratum of mineral and an upper stratum of gangue, this pile is 110 narrowed or pinched as it proceeds along the groove. Consequently, a portion of the upper stratum containing the gangue is forced out of the pile. This material which is forced out is taken up by the wash water 115 and washed over the tailings discharge edge of the table. As the movement proceeds more and more of the gangue is forced out of the pile so that when the material enters the zone 11 between the line A—B and the line 120 C—D, a relatively high and narrow pile is moving in each groove. This pile is still composed of a lower stratum of mineral and an upper stratum of gangue. As the material proceeds through the zone 11, the 125 gradual tapering of the height of the riffles exposes more and more of the upper stratum to the action of the wash water so that more and more of the gangue is washed out as the material proceeds toward the end 5 of the 130

table. As the pinching action is very gradual on account of the considerable extent of this zone the values have time to sink to the bottom of the pile before the water acting 5 on the top of the pile can wash it away. Accordingly, the material which finally emerges from the grooves at the line C—D contains a relatively large amount of mineral and comparatively little gangue. This material then travels over the unriffled zone 12 where a gentle flow of water washes out most of the remaining gangue and delivers a clean 10 concentrate which is discharged over the end 5 of the table.

15 Another consequence of the above described zoning arrangement is that the material flowing over the middle zone 10 of the table is retarded somewhat in its travel along the table by the narrowing of the grooves. This 20 retardation prevents too rapid crowding of the material toward the tail end of the table and consequent denudation of the upper end of the table in the zone 9. By this arrangement of riffles, the material is caused to 25 spread itself over substantially the whole table, including the greater part of the zone 9, and, accordingly, the entire deck is active 30 in the stratification of the material. In this way, although the material is somewhat retarded in the zone 10, the output of the entire table is increased, because the material arrives at the zone 10 in a better state of stratification and a great deal of the gangue is 35 washed off in the zone 9, which, in tables of previous construction, is almost wholly inactive.

It will be seen that this invention provides an improved apparatus for concentrating materials of this kind. First, the coarse concentrates and such fine mineral as may be free 40 from gangue are separated out by the preliminary riffles 8. The remaining material is then stratified so as to separate the concentrates from the gangue in a pile of different strata. 45 This pile is then progressively narrowed or pinched so as to force out the gangue at the top of the pile to be washed away by the water. After such pinching, the pile is further advanced and progressively reduced in height 50 so that the wash water may have an opportunity to operate upon progressively more and more of the upper stratum. The concentrated material is then given a final washing on the unriffled part of the table 12.

55 The steps of this process are carried out in accordance with the arrangement of the riffles on the table. The wide grooves, with narrow riffles, in the zone 9 effect a stratification of the material so as to provide piles of different strata. This material is then moved into the zone 10, where the narrowing of the grooves 60 operates to pinch the piles and force the lighter material out of them. The tapered riffles in the zone 11 then operate as above de-

scribed to gradually reduce the height of the piles.

The specific arrangement as to widths and heights and degree of taper, etc., of the riffles may, of course, be varied to suit the requirements of the particular conditions of operation. Similarly, the relative arrangement and extent of the different zones may be altered 70 as the requirements of the case demand.

It is obvious that various changes may be 75 made in the details of construction without departing from the spirit of this invention; it is to be understood, therefore, that this invention is not limited to the specific details shown and described.

Having thus described the invention, what is claimed is:

1. An apparatus of the character described, comprising, a table mounted and adapted for endwise reciprocating movement, said table 80 having grooves therealong arranged in zones, one of said zones having relatively wide parallel grooves, another gradually tapering grooves and occupying a substantial extent of said table, and another narrow grooves, said 85 narrow grooves becoming progressively shallower toward the tail end of said table.

2. An apparatus of the character described, comprising, a table mounted and adapted for endwise reciprocating movement, said table 90 having grooves therealong arranged in zones, one of said zones having grooves of substantially uniform width extending along the feed edge of said table for a major portion 95 of its length, a second zone adjacent the head end of said table having grooves of uniform width covering a major portion of the width but only a fraction of the length of the table, and another zone following said 100 second zone along and covering a major portion of the width of the table and having tapering grooves.

3. An apparatus of the character described, comprising, a table mounted and adapted for endwise reciprocating movement, said table 105 having grooves therealong arranged in zones, one of said zones having grooves of substantially uniform width extending along the feed edge of said table for a major portion of its length, a second zone adjacent the head 110 end of said table having wide grooves of uniform width covering a major portion of the width but only a fraction of the length of the table, another zone following said second zone along and covering a major portion of the 115 width of the table and having tapering grooves, and another zone having narrow grooves of uniform width.

4. An apparatus of the character described, comprising a table mounted and adapted for 120 endwise reciprocating movement, said table having grooves therealong arranged in zones, one of said zones having grooves of substantially uniform width along the feed side of said table, a second zone adjacent the head 125

end of said table having wide grooves of uniform width, another zone occupying a substantial extent of said table and having tapering grooves, and another zone having narrow 5 grooves of uniform width, said last grooves tapering in depth.

5. A concentrator table, comprising, a rifled deck mounted for endwise reciprocating movement and having a lateral inclination, said deck having grooves arranged in 10 zones including an initial zone having wide parallel grooves, a middle zone of substantial extent having gradually tapering grooves and an end zone having narrow parallel grooves, narrow grooves having a gradually decreasing depth.

6. A concentrator table, comprising, a rifled deck mounted for endwise reciprocating movement and having a lateral inclination, said deck having grooves arranged in 20 zones including a zone originating near the feed end of said deck and having gradually narrowing grooves, and a succeeding zone having parallel narrow grooves of substantially uniform width decreasing gradually in 25 depth toward the discharge end of the table.

7. A concentrator table, comprising, a rifled deck mounted for endwise reciprocating movement and having a lateral inclination, said deck having grooves arranged in 30 zones including an initial zone having parallel grooves of substantially uniform width extending along the upper edge of the table, a second zone originating near the feed end of 35 said deck and having gradually narrowing grooves, and a succeeding zone having parallel narrow grooves of substantially uniform width.

In testimony whereof we affix our signatures this 15th day of October, 1926.
